ENART GOSMANN, OF ELMWOOD PARK, ILLINOIS, ASSIGNOR TO WESTERN ELECTRIC COMPANY, INCORPORATED, OF NEW YORK, N. Y., A CORPORATION OF NEW YORK

SOUND REPRODUCING SYSTEM

Application filed February 10, 1932. Serial No. 592,063.

This invention relates to communication systems and particularly to those systems in which a plurality of originating channels may be connected to a common terminating channel.

The object of the invention is the provision of means for gradually reducing the power transmitted to the terminating channel from one originating channel and gradually increasing the power transmitted to the terminating channel by another originating channel.

A feature of the invention is the provision of switching means which do not involve any sliding contacts in the communication channels.

Another feature of the invention resides in the use of a plurality of thermionic devices for switching the originating channels to the terminating channel.

A further feature of the invention resides in the use of switching devices in which, after the change has been initiated by the attendant, the time of the change is automatically controlled by the switching device.

For convenience of description, the invention has been shown embodied in a sound reproducing system but it will be obvious that the invention may be applied to many other communication systems.

In known sound reproducing systems, in many cases, a plurality of sound records must be reproduced in succession by the same reproducing channel, without producing a noticeable break between the successive records. For example, the known feature presentations generally comprise from five to ten reels of pictures with their corresponding records. At the end of each reel the picture must fade out and the beginning of the next reel must fade in so that the change-over is not perceptible. The sound records may be of any known type such as a photographic record, disc record, magnetic record or other types and are translated into sound modulated electric currents by suitable translating devices. The power delivered to the reproducing channel by the translating device corresponding to the first reel, which may be termed the outgoing translator, must de-

crease at the change-over, while the power delivered to the reproducing channel by the translating device corresponding to the second reel, which may be termed the incoming translator, must correspondingly increase at the change-over.

In accordance with the present invention the output of the outgoing translator is supplied to a thermionic device which supplies an amplified output to the reproducing channel. Similarly, the output of the incoming translator is supplied to a second thermionic device, also connected to the reproducing channel. At the change-over the projectionist operates a switch which opens the cathode circuit of the first thermionic device and closes the cathode circuit of the second thermionic device. The cathode of the first device cools at a rate determined by its design, the electron emission decreases, and the power delivered to the reproducing channel decreases to zero. Conversely, the cathode of the second device heats up, the electron emission increases, and the power delivered to the reproducing channel increases to normal.

If the cathode circuit of the second device is closed by the same operation which opened the cathode circuit of the first device, the two devices will operate simultaneously decreasing the output from the outgoing translator while the output from the incoming translator is increasing. The time taken to make the change-over will then be determined by the design of the cathode circuits only and may be correlated to the length of the fade-out and fade-in on the picture reel.

By permitting a short time to elapse between the opening of the first cathode circuit and the closing of the second cathode circuit, the output from the outgoing translator may be permitted to fall to a small value before the output of the incoming translator is supplied to the reproducing channel.

The drawing discloses in schematic form an embodiment of the invention.

Modulated currents from a translating device 1 are amplified in an amplifier 2 and applied through a transformer 3 to the input of a thermionic amplifier 4. The amplified currents in the output of the ampli-

fier 4 are supplied to a transformer 5, and may be amplified in a suitable amplifier 6. The amplified output of the amplifier 6 may be utilized in any desired manner, for example, as shown, the amplified output may 5 actuate a reproducing device 7.

The communication channel formed by the translating device 1, amplifier 2, transformer 3 and amplifier 4 may conveniently be 10 termed an originating channel. Similarly, the communication channel formed by the transformer 5, amplifier 6, and reproducing device 7 may be termed a terminating channel.

15 Current is supplied from battery 8 through the primary winding of transformer 5 to the anode of the amplifier 4, thence through amplifier 4 to its cathode and through the ground to battery 8. Current is also supplied from battery 9 through resistor 10, springs 20 11 and 12, cathode of amplifier 4, through the ground to battery 9. The currents from batteries 8 and 9 energize the amplifier 4.

A key 13 may be located at any point convenient to the operator. When key 13 is 25 closed, current flows from battery 14, through key 13 and the winding of a relay 15. Relay 15 is energized and closes a circuit between springs 11 and 16, and then opens the circuit 30 between springs 11 and 12. When the circuit is opened between springs 11 and 12 current ceases to flow in the cathode of the amplifier 4 and the modulated power from the translating device 1 supplied to the reproducer 7 decreases and finally becomes negligibly small. When the circuit is closed between springs 11 and 16, current can flow 35 from battery 9, through resistor 10, springs 11 and 16, cathode of a thermionic amplifier 17, through ground to battery 9. Modulated currents from a translating device 18 are amplified by an amplifier 19 and applied through 40 a transformer 20 to the amplifier 17. When current is applied to the cathode of the amplifier 17, the amplified output of the amplifier 17 will gradually increase to normal. The output of the amplifier 17 is supplied 45 through transformer 5, and amplifier 6 to the reproducing device 7. Current from 50 battery 8 is supplied through the primary winding of transformer 5 to the anode of the amplifier 17 and flows through the amplifier 17 to ground and thence to battery 8, energizing the output circuit of the 55 amplifier 17.

The cathode of the amplifier 4 will take an appreciable time to cool and similarly, the cathode of the amplifier 17 will take an appreciable time to heat up to normal. During 60 the time in which the cathode of the amplifier 4 is cooling, the modulated power transmitted from the translating device 1 to the reproducing device 7 will gradually decrease. Similarly, during the time in which the 65 cathode of the amplifier 17 is heating, the

modulated power transmitted from the translating device 18 to the reproducing device 7 will gradually increase. The terminating channel has thus been switched from one originating channel to another.

70 The relay 15 may be replaced by any suitable key and may be arranged so that the modulated power transmitted by the amplifier 4 falls to a small value before the cathode circuit of the amplifier 17 is energized.

75 The translating devices 1 and 18 are shown reproducing a disc sound record rotated by a conventional turntable. Obviously, these translating devices may take a variety of forms suitable for translating other types of sound records, such as photographic, magnetic or chemical records, or may be conventional microphones which translate acoustic waves into modulated electric waves.

80 What is claimed is:

1. In combination, a plurality of originating communication channels individually connected to the inputs of a plurality of thermionic devices, said devices each having an anode, a cathode and a control electrode, a terminating communication channel connected to the outputs of all of said thermionic devices, and switching means for energizing the cathode of one of said thermionic devices and, at will, deenergizing the cathode of said thermionic device and energizing the cathode of another of said thermionic devices.

85 2. In combination, a plurality of devices for translating individual sound records into modulated electric waves, a plurality of thermionic devices individually controlled by said modulated waves, said devices each having an output circuit, an input circuit and a cathode, sound reproducing means connected to the outputs of all of said thermionic devices and switching means for energizing the cathode of one of said thermionic devices and, at will, deenergizing the cathode of said thermionic device and energizing the cathode of another of said thermionic devices.

90 In witness whereof, I hereunto subscribe my name, this 1st day of Feb. 1932.

ENART GOSMANN.
